UNITED STATES PATENT OFFICE.

PHILIP K. YOUNG, OF OMAHA, NEBRASKA.

GROOVE-FILLING DEVICE FOR STREET-RAILWAY CROSSINGS.

939,463.

Specification of Letters Patent.

Patented Nov. 9, 1909.

Application filed December 30, 1908. Serial No. 470,100.

To all whom it may concern.

Be it known that I, PHILIP K. YOUNG, a citizen of the United States, residing at Omaha, in the county of Douglas and State 5 of Nebraska, have invented certain new and useful Improvements in Groove-Filling Devices for Street-Railway Crossings, of which the following is a specification.

This invention relates to improvements in 10 groove-filling device for street railway crossings, and has for its object, broadly, the provision of means for preventing vibrations or shocks to the car, caused by the wheels striking against the transverse rails when passing a crossing.

Another object is the provision of a structure for this purpose which may be economically manufactured and which may be conveniently placed in operative position, or removed when desired.

The ordinary construction of an integral, metal framework for street car crossings is attended with a considerable expense, and where any of its parts become worn or 25 broken by action of the wheel flanges the expense for labor and material for replacing the same is very great. By use of the herein described device the grooves at the intersections are filled, and the cars may cross intersections without the usual vibration, since 30 the wheels or flanges do not make contact with the transverse walls of the rails at the crossings. Also when the grooves become enlarged by continued wear of the wheel flanges the device may be readily removed and replaced without disturbing the integral framework.

The invention has reference to the employment of an angular member, preferably 40 formed as an integral metal casting having arms extending outwardly from its middle, the arms of the structure having their lower surfaces disposed upon a single plane, their upper surfaces being longitudinally grooved 45 and downwardly inclined in the direction of their terminals, the device to be partly countersunk in a recess formed at the bottom of the groove of the track rail to cover the grooves at the intersections of the rails.

The invention consists of the novel combination and arrangement of parts as described herein, pointed out by the claim and as illustrated in the drawing, wherein,—

Figure 1 is a plan view of a trackway intersection with groove-filling devices thereon, embodying my invention. Fig. 2 is a

side view of a trackway, being a view sectioned on line *a a* of Fig. 1, car wheels being added. Fig. 3 is a plan view of the angular groove-filling device. Fig. 4 is a side view 60 of the same, being a view sectioned on line *ff* of Fig. 3. Fig. 5 is an enlarged side view of the invention, being a view sectioned on line *b b* of Fig. 1, parts being broken away. Fig. 6 is an enlarged, broken away view 65 showing a part of the device, and is a detail figure relating to Fig. 3.

Referring now to the drawing for a more particular description, numeral 1 indicates a rail or car track, and the intersecting framework employed ordinarily consists of the integral, interior, square frame 2, operating as guide-rails; at 3 are indicated four intermediate heading-frames, each having body-portions 4 operating as track-rails and having angular arms 5 operating as guide-rails; at 6 are indicated L-shaped outer frames each having body-portions 7 and 8, operating as track-rails. The parts of the framework thus described, with the exception of 80 frame 2, are secured to the ends of rails 1 so that the parts to form the crossing will be in alinement, the height of the guide rails and adjacent track being substantially equal, and thereby are formed longitudinal grooves 85 or recesses 9 between each track and guide rail, each track having vertical walls 10.

The operation of a car passing track intersections is attended with shocks and vibrations by reason of the wheels striking upon 90 walls 10 while crossing recesses 9, and continued operation results in flattening, breaking or the wearing away of walls 10, and the repairing thereof, as above stated, is a matter of considerable expense. In order that 95 these objectionable features may be avoided, I provide a metallic groove-filling device 11 having a flat bottom 12 and an upper, middle, flat platform 13 from which arms 14 and 15 extend outwardly. Arms 14 are in 100 alinement with reference to each other; arms 15 are also in alinement, and where trackways cross at right angles, as shown in Fig. 1, arms 14 are disposed at right angles to arms 15.

The lower surfaces 12 of arms 14 and 15 are formed to occupy the same plane and are seated in recesses 16, chamfered in the parts of the intersection framework which forms the trackways between walls 10, and when 110 operatively seated in recesses 16 they require no holding means for securing them to the

tracks. The upper surfaces 19 of these arms are formed downwardly inclined from the middle platform 13 to their terminals, and along these surfaces are formed longitudinal 5 grooves 20, these grooves being formed near one of the edges of said inclined surface, thereby providing longitudinal ridges or guides 21, and as thus described grooves 20 and guides 21 extend inwardly from the terminals of arms 14 and 15 and terminate at platform 13.

In operation, when the car is moving, flanges 17 of wheels 18 will pass from an engagement within grooves 9 and will be 15 engaged within grooves 20 of the device as they pass upward upon the inclined wall 19, and as they approach platform 13 the wheels will be elevated somewhat above the tracks, as shown in the drawing, the weight at this 20 time being sustained by the flanges while resting within grooves 20. After reaching platform 13 the wheels may pass downward upon the opposite arm, flanges 17 being in engagement with grooves 20 of said opposite 25 arm, during the descending movement, and since there are no obstructions to be encountered by the wheels, there will be no shocks or vibrations.

It will be noted that in the use of the invention, no change is required in the con-

struction of the ordinary framework employed for intersections, except the formation of recesses 16, and if the device should be accidentally broken or injured, or, by action of the flanges the grooves 20 become 35 enlarged, the same may be replaced at slight comparative expense.

Having fully described my invention, what I claim as new and desire to secure by Letters Patent is,—

The combination with a plurality of rails crossing each other at an angle, of a groove filling device therefor, comprising a spider, each arm of which is curved downwardly from the intersection of said arms to the outer end thereof, each of said arms having an upstanding rib entirely along one edge thereof, said spider being flat upon its under face and being seated in recesses which are in addition to the usual grooves of the rails 50 whereby the extreme ends of the lowest portions of the arms of the spider lie flush with the bottom of the usual grooves of the rail, substantially as described.

In testimony whereof I have affixed my signature in presence of two witnesses.

PHILIP K. YOUNG.
